UNITED STATES PATENT OFFICE.

JOHN F. O'CONNOR, OF CHICAGO, ILLINOIS, ASSIGNOR, BY MESNE ASSIGNMENTS, TO
W. H. MINER, INC., A CORPORATION OF DELAWARE.

HAND BRAKE FOR RAILWAY CARS.

Application filed March 6, 1922. Serial No. 541,314.

This invention relates to improvements in hand brakes for railway cars.

The standard practice for many years on freight cars with respect to the hand brakes has included the use of a vertical brake staff passing through a small platform or step for the brakeman and with a hand wheel at the top thereof. To hold the staff against rotation in an unwinding direction, it has been customary to employ a latch wheel located immediately above the step and with which cooperates a dog manipulated by the brakeman's foot. Said type of brake is unsatisfactory and more or less dangerous to the brakeman on account of the fact that he is required to use both hands on the hand wheel in applying the brake, thus leaving him without adequate support or balance, in the event of accident to any part, or sudden loss of his hold upon the hand wheel.

During the last few years, there has been a gradual change from the old hand wheel vertical staff type of brake to a brake of the ratcheting type which permits the brakeman to employ one hand in effecting the winding up of the brake chain and leaves him free to use the other hand to grasp a hand grip on the car.

In making the change from the old practice to the more modern practice, it is desirable that as much of the old equipment be re-employed as possible, in order to reduce expenditures of the railroads and without sacrifice of any of the advantages of the more modern type of brake of the ratcheting type.

The object of my invention is to provide an arrangement for vertical staff types of hand brakes for railway cars, which is relatively inexpensive and which may be substituted for the usual hand wheel so that the original brake staff, latch wheel and locking dog, may be re-employed while at the same time allowing the brakeman always to utilize one hand in supporting himself on the car.

In the drawings forming a part of this specification, Figure 1 is a part horizontal, sectional view, part top plan of a portion of a car showing my improvements in connection therewith. Figure 2 is a vertical, sectional view, corresponding substantially to the line 2-2 of Figure 1. Figure 3 is a horizontal, sectional view, corresponding to

the section line 3-3 of Figure 2. Figure 4 is a view similar to Figure 1, illustrating another embodiment of the invention. And Figure 5 is a vertical, sectional view, corresponding to the section line 5-5 of Figure 4.

Referring first to the construction illustrated in Figures 1, 2 and 3, 10 denotes the end wall of a car, 11 the usual brakeman's step or small platform on the end wall, 12 the usual vertical brake staff, 13 the usual latch wheel keyed or splined to the staff, and 14 the usual pivotally mounted foot-operated locking dog cooperable with the latch wheel.

In lieu of the usual hand wheel and the usual bearing bracket for the upper end of the staff, I substitute the following arrangement. Secured to the wall 10 of the car is a combined housing and bearing bracket designated generally by the reference A, the same having a back wall 15 riveted to the wall 10 of the car, a top horizontally extending wall 16 and a lower horizontally extending wall 17, together with vertically extending webs 18 and 19 which terminate at the points 20 and 21, respectively, so as to leave an arc of a little more than 90° for the oscillating movements of the operating handle and associated parts. As is clear from an inspection of Figure 2, the upper and lower walls 16 and 17 provide bearings for the staff.

Keyed or otherwise rigidly secured to the staff 12, midway between the walls 16 and 17, is a friction drum 22 having a series of V-shaped ribs 23 extending annularly therearound.

Oscillatably mounted on the staff 12 at points above and below the drum 22, are links 24 and 25, forming a carrier, to which is oscillatably connected a block 26 having upper and lower vertically extending studs 27-27 entering corresponding bearing openings in said links 24 and 25. The block 26 is extended outwardly beyond the periphery of the curved walls 16 and 17 and has pivotally secured thereto by a horizontally extending pivot bolt 28, a gravity drop handle 29.

The block 26, as best indicated in Figure 1, is provided with a hub 30 arranged eccentric to the axis of the studs 27-27, said eccentric hub 30 fitting within a corresponding

recess provided in a friction shoe 31, said recess being defined by two flanges 32—32 which encircle more than 180° of the circumference of the eccentric hub 30 so that, upon oscillation of the block 27 about its pivotal mounting on the links 24 and 25, said friction shoe 31 will be positively moved inwardly and outwardly radially with respect to the drum 22. The shoe 31 extends through an arc of approximately 150° and is ribbed on its arcuate face as indicated at 33 to frictionally engage the ribs of the drum 22.

In actual practice, the eccentric hub 30 will be so positioned with respect to the pivotal axis of the block 26, that, as the operating handle or lever 29 is pulled toward the brakeman, that is, in a clockwise direction as viewed in Figure 1, the eccentric hub 20 30 will move toward the axis of the staff and thereby press the shoe into tight frictional engagement with the drum and thus cause the drum and staff to be correspondingly rotated step by step, when 25 the operating handle is swung in the opposite direction, in such manner as to oscillate the block 26 about its pivotal axis on the links 24 and 25, the eccentric hub 30 will be withdrawn or moved away from the drum, thus moving the friction shoe correspondingly and positively disengaging the friction shoe from the drum. As the drum and staff are rotated in a winding direction 30 step by step, by what may be termed the ratcheting action, they are held against reverse rotation by the foot-operated dog 14 being thrown into engagement with the latch wheel 17.

With the arrangement shown, it will be seen that my improvements may be applied at comparatively small expense both for material and labor; I obtain the desirable ratcheting action; and also allow the brakeman to use one hand in supporting himself 45 from the car. Furthermore, by employing the friction shoe 31 and friction drum 22, the brakeman is enabled to "ease off" the brakes, thereby permitting him to "spot" the cars accurately.

In the arrangement shown in Figures 4 and 5, the staff 112 is journaled in a box-like housing or bracket A' having a bottom wall 117, top wall 116, side walls 118 and 119 and an end wall 40. Only one journal bearing 50 for the staff is provided, the same being by the bottom wall 117. As clearly shown in Figure 4, the box-like housing or bracket is extended at an angle from the wall 110 of the car and in a direction away from the position occupied by the brakeman, for the purpose hereinafter described.

Secured to the staff 112 within the housing A' is a bevel gear 41 adapted to cooperate with another bevel gear 42 mounted on a horizontal stud shaft 43, which is journaled

at its inner end in a suitable bearing 44 of the housing A' and at its outer end in a bearing 45 on the end wall 40.

Within the housing A', the shaft 43 has a friction drum 122 secured thereto with which cooperates a friction shoe 131 mounted on an eccentric hub 130 of a hand lever 129 which is pivotally connected to a pair of links 124—125 in turn oscillatably mounted on the stud shaft 43. As will be understood by those skilled in the art, the customary latch wheel and foot-operated dog will be employed with the staff 112 as shown in Figures 1, 2 and 3 in connection with the other embodiment of my invention.

By introducing the bevel gears and extending the housing A' and stud shaft 43 at an angle to the end wall of the car and in a direction away from the brakeman, I am enabled to position the handle 129 conveniently for the brakeman and without crowding him while permitting him to operate the brake by lifting the handle in a vertical plane instead of swinging it in a horizontal plane. Some brakeman prefer the so-called pump handle type of ratchet brake in which the operating handle is moved up and down, inasmuch as it is thought that this allows the brakeman to use more force in applying the brake. With my arrangement, the brakeman may stand upon the usual step or platform and support himself from the car with one hand while using the other or right hand in operating the brake with ample clearance and freedom from danger.

I have herein shown and described what I now consider the preferred manner of carrying out the invention, but the same is merely illustrative and I contemplate all changes and modifications that come within the scope of the claims appended hereto.

I claim:

1. In a hand brake for railway cars having a brake step, the combination with a vertical staff extending through the step and having a latch wheel secured thereto adjacent the step and a foot-controlled dog co-operable with the latch wheel; of a bearing bracket for the upper end of the staff; and means for rotating said staff step by step including, a grooved friction drum, a carrier oscillatable about the axis of the drum adjacent the latter, a grooved friction shoe co-operable with the drum, and an operating handle supported from said carrier and adapted to oscillate with respect thereto to force said shoe against the drum, said handle being movable to inoperative position to actuate and hold said shoe in inoperative position with respect to the drum.

2. In a hand brake for railway cars having a brake step, the combination with a vertical staff extending through the step and having a latch wheel secured thereto ad-

- adjacent the step and a foot-controlled dog cooperable with the latch wheel; of a bearing bracket for the upper end of the staff; and means for rotating said staff step by step 5 including, a friction drum, a carrier oscillatable about the axis of the drum, a member mounted on the carrier to oscillate about an axis parallel to the axis of the drum, said member having an eccentric section, and a 25 friction shoe cooperable with the drum mounted on said eccentric section.
6. In a hand brake for railway cars having a brake step, the combination with a vertical staff extending through the step and having a latch wheel secured thereto adjacent the step and a foot-controlled dog cooperable with the latch wheel; of a bearing bracket for the upper end of the staff; and 10 means for rotating said staff step by step 15
7. In a hand brake for railway cars having a brake step, the combination with a vertical staff extending through the step and having a latch wheel secured thereto adjacent the step and a foot-controlled dog cooperable with the latch wheel; of a bearing bracket for the upper end of the staff; and 20 means for rotating said staff step by step 25
8. In a hand brake for railway cars having a brake step, the combination with a vertical staff extending through the step and having a latch wheel secured thereto adjacent the step and a foot-controlled dog cooperable with the latch wheel; of a bearing bracket for the upper end of the staff; and 20 means for rotating said staff step by step 30
9. In a hand brake for railway cars having a brake step, the combination with a vertical staff extending through the step and having a latch wheel secured thereto adjacent the step and a foot-controlled dog cooperable with the latch wheel; of a bearing bracket for the upper end of the staff; and 25 means for rotating said staff step by step 35

including, a friction drum, a carrier oscillatable about the axis of the drum, a member mounted on the carrier to oscillate about an axis parallel to the axis of the drum, said member having an eccentric section, and a friction shoe cooperable with the drum mounted on said eccentric section.

4. In a hand brake for railway cars, the combination with a brake staff; of means for rotating said staff in a direction to tighten the brakes, said means including a clutch element and an operating lever mounted for swinging movement about the axis of said staff, said lever including a pivoted arm portion provided with an eccentric head coacting with said clutch element.

In witness that I claim the foregoing I have hereunto subscribed my name this 17th day of Feb., 1922.

JOHN F. O'CONNOR.
